UNITED STATES PATENT OFFICE.

FRED B. COREY, OF SCHENECTADY, NEW YORK, ASSIGNOR TO GENERAL ELECTRIC COMPANY, A CORPORATION OF NEW YORK.

AUTOMATIC TRAIN-STOP.

No. 851,800.

Specification of Letters Patent.

Patented April 30, 1907.

Application filed September 19, 1906. Serial No. 335,236.

To all whom it may concern:

Be it known that I, FRED B. COREY, a citizen of the United States, residing at Schenectady, county of Schenectady, State of New York, have invented certain new and useful Improvements in Automatic Train-Stops, of which the following is a specification.

My invention relates to automatic train-stops, and consists in an improvement of the invention described in Patent No. 828,386, granted to me August 14, 1906.

It has frequently been the custom heretofore to employ stop-arms controlled by signals arranged to engage a brake-controlling device on a passing car, so as to apply the brakes if the car tries to pass a signal set at danger. It is sometimes desirable to permit a train to pass a danger signal at low speed, and the arrangement of my former patent had this object in view. To accomplish this result, in the arrangement of my former patent the stop-arm was made flexible, but with high inertia, so as to yield if struck by a slowly moving object; but to offer high resistance if struck by a rapidly moving object.

By my present invention I am enabled to make the stop-arm, which is less accessible for inspection and repair than the parts on the car, in the form of a rigid iron bar controlled by the signal. I secure this result by placing on the car a movable member possessed of high inertia with a controlling device on the car adapted to be engaged by this member upon its movement beyond a predetermined limit. On a slowly moving car this movable member, on engaging the stop-arm, is moved only a sufficient amount to allow it to pass the arm; but on a rapidly moving car, owing to its inertia, the movable member will be swung a much greater distance, so as to engage the controlling device.

My invention will best be understood by reference to the accompanying drawings, in which

Figure 1 shows a train-stop apparatus arranged in accordance with my invention; Fig. 2 shows on a larger scale the connection between the stop-arm and the signal; and Fig. 3 shows the apparatus on a still larger scale with particular reference to the parts on the car.

In the drawings, A represents a block signal, which controls by a mechanical or other operative connection an arm B, which is

placed beside the track. The arm is raised 55 into the position shown when the signal is at danger and lowered when the signal is at clear position.

C represents a car carrying the weighted pendulum D, which is designed so as to possess high inertia, in a position to be engaged by the stop-arm B. If the car is moving slowly, the pendulum D on striking the stop-arm will be moved only a sufficient distance to enable it to slide over the stop-arm, but on 60 a rapidly moving car the impulse given to the pendulum by the stop-arm will carry it to a practically horizontal position, in which its cam-shaped upper surface engages and opens the pilot-valve E, shown in dotted lines in 70 Fig. 3. This pilot-valve, which may be of any suitable construction, controls a brake-controlling valve F by exhausting the air from the upper side of a piston G, which is normally exposed on both sides to the train-pressure, and which is normally held in the position shown by a compression-spring H. The piston G carries a normally-closed valve I, which, when the piston rises, exhausts the train-pipe J. In order to hold the relay- 80 valve E open, catches K are provided, which hold the pendulum D in horizontal position, and consequently in engagement with the relay-valve.

I do not desire to limit myself to the particular construction and arrangement of parts here shown, but aim in the appended claims to cover all modifications which are within the scope of my invention.

What I claim as new and desire to secure 90 by Letters Patent of the United States, is,—

1. An automatic train-controlling device comprising a stop-arm on the roadway, a movable member on a car possessing high inertia and adapted to be engaged by said stop-arm, and a controlling device on the car arranged to be operated by a movement of the movable member beyond predetermined limits.

2. An automatic train-controlling device 100 comprising a stop-arm on the roadway, a movable member on a car possessing high inertia and adapted to be engaged by said stop-arm, and a brake-controlling valve on the car arranged to be operated by said member upon its movement beyond predetermined limits.

3. In a block signal system for railways, a

signal, a stop-arm controlled thereby, a movable member on a car possessing high inertia and adapted to be engaged by said stop-arm, and a controlling device on the car arranged to be operated by a movement of the movable member beyond predetermined limits.

4. In a block signal system for railways, a signal, a stop-arm controlled thereby, a movable member on a car possessing high inertia and adapted to be engaged by said stop-arm, and a brake-controlling valve on the car arranged to be operated by a movement of said member beyond predetermined limits.

5. In a block signal system for railways, a signal, a stop-arm controlled thereby, a movable member on a car possessing high inertia and adapted to be engaged by said arm, a relay valve arranged to be struck and opened by said member upon a movement thereof beyond predetermined limits, and a brake-controlling valve controlled by said relay valve.

6. In a block signal system for railways, a signal, a stop-arm controlled thereby, a movable member on a car possessing high inertia

and adapted to be engaged by said arm, a relay valve arranged to be struck and opened by said member upon a movement thereof beyond predetermined limits, a brake-controlling valve controlled by said relay valve, 30 and a catch adapted to engage said member upon its movement into engagement with the relay valve.

7. In a block signal system for railways, a signal, a stop-arm controlled thereby, a movable member on a car possessing high inertia and adapted to be engaged by said stop-arm, a brake-controlling device on the car arranged to be operated by a movement of said member beyond predetermined limits, and a 35 catch adapted to engage said member upon its movement into engagement with said device.

In witness whereof, I have hereunto set my hand this 18th day of September, 1906. 45

FRED B. COREY.
